UNITED STATES PATENT OFFICE.

ROBERT F. JONES, OF EASTPORT, MAINE, ASSIGNOR TO WM. WALTKE & CO., OF ST. LOUIS, MISSOURI, A CORPORATION OF WEST VIRGINIA.

MACHINE FOR BOXING SARDINE-CANS AND THE LIKE.

1,337,404.

Specification of Letters Patent. Patented Apr. 20, 1920.

Application filed June 9, 1915. Serial No. 33,154.

To all whom it may concern:

Be it known that I, ROBERT F. JONES, a citizen of the United States, residing at Eastport, Maine, have invented a certain new and useful Improvement in Machines for Boxing Sardine-Cans and the like, of which the following is a specification.

My invention relates to a machine by means of which the usual small tin or can of packed sardines, as ordinarily sold to the consumer, may be inclosed in a suitable pasteboard container for merchandizing purposes.

More particularly my invention relates to a machine of the character specified by means of which certain types of prepared containers or cartons, commercially manufactured in collapsed flat form, may be placed in bulk in a suitable magazine, with drawn singly therefrom and then opened, the packed sardine can placed therein, and the container then closed ready for shipment and sale.

Machines for packing matches, cigarettes, seeds and other articles in cartons are not new, but I am not aware that any machine has hitherto been invented or used which is capable of filling and closing a type of carton suitable for sardine cans; nor do I know of any such earlier machine capable of packing sardine cans in any kind of carton, suitable or unsuitable.

My invention will be better understood by referring to the accompanying drawings showing a preferred form of my invention. In these drawings Figure 1 represents a front elevation of the machine, part being broken away; Fig. 2 represents a central longitudinal section through Fig. 1; Fig. 3 is a plan view of the machine, taken from above; Fig. 4 is a transverse section, enlarged, along the line 4—4 of Fig. 3; Fig. 5 is a transverse section along the line 5—5 of Fig. 3; Fig. 6 is a view, similar to Fig. 4, along the line 6—6 of Fig. 3; Fig. 7 is a central longitudinal section, enlarged, from about the center to the delivery end of the machine as indicated by the line 7—7 of Fig. 3; Fig. 8 is a plan view, still further enlarged, of the carton end flap folding mechanism; Fig. 9 is a central longitudinal section, enlarged, through the magazine and

carton delivering means; Fig. 10 is a plan view of Fig. 9; Fig. 11 is a plan view of Fig. 9, taken from below; Fig. 12 is a transverse section taken through the line 12—12 of Fig. 11; Fig. 13 is a plan view of the collapsed carton positioned as it lies in the magazine; Figs. 14 and 15 are, respectively, a side elevation and a perspective view of the carton opened up for the reception of a sardine can but before either ends or lips are closed; and Fig. 16 represents an enlarged detail, in side elevation, of the star shaped cam which operates the carton depressing finger.

Briefly described the machine of my invention comprises a table having at one end a magazine in which a large number of collapsed cartons may be stacked. A slide is arranged to intermittently move across the bottom of the magazine so as to remove one carton at a time, which carton is carried forward, opened, and placed in opened condition in a compartment of a linearly disposed chain conveyer. This conveyer is then advanced and the filled compartment brought opposite a laterally disposed intermittently rotatable table upon which the packed sardine cans are placed, the lips at the end of the carton remote from the sardine can being simultaneously closed. As the cartons successively stop opposite this table a sardine can is swept into the carton by a suitable wiping device. The chain is then advanced, the remaining lips and both end flaps of the carton folded in, and the filled carton delivered from the other end of the machine.

In the descriptive matter herein, the side of the machine upon which the loose and driving pulleys are located is referred to as the rear, and the opposite side as the front of the machine; the end of the machine opposite the magazine is called the delivery end of the machine; the end of the carton into which the sardine can is inserted is termed the receiving end and the opposite end of the carton, the outer end.

In the drawings the operative mechanism is carried by a skeleton frame 1 comprising a base, two sides, and a top or table. The machine is driven from a main shaft, 2, by means of a main pulley, 3; a loose pulley, 4,

may be used when it is desired to throw the machine out of action. The shaft, 2, carries the driving element, 5, of a Geneva stop, the receiving or driven element of which, 6, 5 is carried by a suitable stub shaft, 7, mounted on one of the side frames. Shaft 7 has fixed upon it two sprocket wheels 8 and 9, the former carrying a chain 10 driving a sprocket wheel 11, of the same diameter as 10 wheel 8, at the delivery end of the machine, and the latter driving a chain 12 which actuates a sprocket 13, twice the diameter of wheel 9, fixed upon a transverse shaft 14. Sprocket wheel, 11, is fixed to a shaft 15 which carries a pair of sprocket wheels, 15, between which and a second pair of sprocket wheels, 16, mounted at the other (magazine) 20 end of the machine, is carried a conveyer chain, 17, the links of which are provided with spaced pairs of outwardly projecting pins carrying transverse partitions, 18, whereby are constituted compartments, 19, which receive and carry the cartons from one end of the machine to the other as the 25 various operations, to be later described, are performed.

Fixed upon shaft, 14, at the end opposite sprocket wheel, 13, is a bevel gear, 20, which meshes with a similar gear, 21, of half the 30 diameter; this drives a vertical shaft upon the top of which is fixed a rotatable cam feeding table, 22, disposed laterally of and substantially flush with the upper surface of the table.

35 A cam, 23, is keyed upon main shaft, 2, and provided with a face groove 24 which is engaged by a pin, 25, carried at the upper end of a link 26 having its lower end pivoted upon a transverse shaft, 26', fixed to the 40 frame. A horizontally disposed connecting rod 27 has its one end pivoted upon pin 25 and its other end pivotally attached to one end of a lever 28 fulcrumed upon the frame at 29. The other end of lever 28 is pivoted 45 to a link 30 which is itself connected to a lug 30' of a slide 31 mounted on the under side of the magazine table 32.

The magazine, 33, is mounted upon the magazine table 32, at the receiving end of 50 the machine, and is, substantially, a tall, skeleton sided, lidless compartment dimensioned to receive a stack of collapsed cartons 34. The construction of these cartons will, it is thought, be clear from Figs. 13 to 15. They are, preferably, of light card board. After the carton has been opened up, as in Figs. 14 and 15, if it is desired to close the carton, the lips *a*, *b*, and *c*, *d*, at the 55 two ends are first folded in laterally. The end flap, *e*, is then bent upwardly and inwardly so as to fold along the dotted line, *f*, which will coincide with the top end edge, *i*, of the box proper when the carton is completely closed, while the other end flap, *g*, is 60 similarly bent downwardly and inwardly 65

and folded along the line, *h*, which will coincide with the bottom end edge, *j*, of the finally closed box.

Slide 31 comprises a transverse tie piece 35 which unites a pair of carton pusher fingers 36 each of which has tongue and groove engagement with the magazine table so as to be longitudinally slidable therein. The inner end of each finger is inclined upwardly and has a transverse, substantially right angled notch, 37, formed therein, so as to provide a forwardly extended wedge-shaped upper edge which projects above the bottom of magazine 33 by an amount not to exceed the thickness of a single carton, two slots 38 being cut in said bottom for this purpose. The edge *m* of the carton fits in the notch 37 as the carton is being fed from the magazine and the carton walls adjacent said edge will rest against and be pressed upon by the walls of the notch as the pusher fingers feed the carton into its conveyer chain compartment.

Also mounted upon main shaft 2 is an eccentric 39 provided with an eccentric rod 40 which is connected with one arm of a bell crank lever 41 pivotally mounted upon a transverse shaft 41'. The other arm of the bell crank lever, by a pivotally attached link 42, is connected with an arm of a vertically pivoted bell crank lever 43 on the forward side of the table and the other arm of this last named bell crank, by a cross link 43', to one arm of a similarly disposed bell crank lever 44 on the opposite side of the 100 table.

Attached to bell crank lever, 43, so as to move with it, is a folder arm, 45, which serves to turn in the lip *c* at the outer end of the carton, while a link 45' connects bell crank 44 to a transversely pivoted lip folder, 45², on the other side of the machine, for turning in the corresponding lip *a* at the receiving end of the carton, as will later be described.

110 Fixed upon the same shaft as bell crank lever, 41, but at the other side of the machine, is an upstanding operating arm, 46, connected by a link, 47, to the shorter arm of a bell crank lever, pivotally mounted upon a bracket, 48, carried by the frame; the longer arm, 49, of this lever constitutes a wiping device or can delivering sweep for forcing the packed sardine can into the mouth or receiving end of the carton.

115 Pivotaly mounted upon the magazine table, 32, so as to swing parallel therewith and projecting centrally and forwardly to about the inner edge of the slots, 38, is a pair of carton opening knives, 50, the lower 120 surfaces of which are parallel with the surface of the magazine table and spaced therefrom by an amount substantially equal to the thickness of the material of which the carton is made. The upper surface is 130

beveled to a sharp inner edge, 51. The knives, 50, tend ordinarily to be drawn toward one another and against stops, 52, by springs, 53 (Fig. 11).

- 5 On the front side of the magazine table, between knife 50 and the stack of cartons, is a flat boss 54 raised above the surface of the table by an amount equal to the thickness of two or three cartons, or say $\frac{1}{8}$ " to 10 $\frac{3}{16}$ "; and in about the same relative position on the other side of the table is a similar depression 55.

Bent leaf springs, 56, are fixed upon the delivery end of the magazine and exert a 15 gentle pressure upon the top of the magazine table; one of these springs is disposed so as to extend into depression, 55.

The outer face of sprocket wheel, 13, carries a solid cam, 56', provided with a peripheral guide surface, 57, (having the form of an eight pointed star) with which is engaged a pin, 58, at one end of a connecting link 59; the other end of this link is pivotally attached to a crank arm, 60, which is 25 fastened to a transverse shaft, 61, having fixed thereon, at its center, a carton depressing finger, 62; a spring 62', tends to keep this finger in its lowermost position at all times.

30 Fixed to opposite sides of slides 31 and beneath the magazine table, (Fig. 11), is a pair of knife operating screws, 63. As the slide moves forwardly the points of these screws contact with arms, 64, attached to 35 and moving with knives, 50, (but on the lower side of the table) and throw the knives outwardly against the resistance of springs, 53. These screws are adjustable linearly so that the point at which, in the 40 movement of the slide, the knives, 50, are thrown outwardly, may be varied.

Transverse bridges 65, 66, 67, overhang the conveyer chain; from the ends of these bridges are suspended longitudinally disposed flat guide bars, 68, 69, parallel with the top of the machine and distanced from it by an amount just sufficient to lightly press against the top of the carton when the latter is opened up (Fig. 4). The outer 50 edges of these guide bars coincide with the ends of the carton proper.

At the front and rear of the machine, a short distance before bridge, 66, is reached, and just outside the ends of the carton proper are vertical strips, 70, 71, the former suspended from guide bar, 68, and the latter supported from the top of the machine. The ends of these strips toward the magazine are bent laterally outward so that, as 60 the carton is carried along by the conveyer chain, the lips, *b* and, *d*, will contact with these outwardly bent portions and be turned in against the contained sardine can.

At each end of the bridge 66 are pins, 72, 65 73, which carry short folder plates, 74, 75,

which are parallel with strips 70, 71, and separated from them by an amount corresponding to the distance between lines *h* and *f* respectively, of the carton end flaps, and the lines *j* and *i* which represent the 70 ends of the carton proper. The rear folder plate, 74, is spaced slightly away from the machine top while the other folder plate, 75, is similarly spaced away from an upper bar 76, flush with and just outside of bar 69. 75

At the rear of the machine, just outside plate, 74, and of equal length therewith, is a strip, 77; the end of this strip nearest the magazine lies flat upon the machine top but the outer edge of the strip is twisted upwardly and inwardly through a right angle 80 so that its other end is parallel with and closely adjacent to plate 74.

A strip, 78, similar to strip, 70, is held against the lower side of bar, 76, just outside of folder plate 75.

Fixed upon the rear of the machine top, and extending from just beyond bridge, 66, to the delivery end of the machine, is a carton closing trough, 79. This is, preferably, 90 a bar in the inner side of which is formed a channel or trough into which the end flap of the carton passes from the folder plate and strip. At the end toward the magazine this trough has a horizontal wall, 80, which 95 lies upon the machine top and a vertical outer boundary wall, 81. As the channel advances toward the delivery end of the machine it continuously twists clockwise until, at its end, the vertical wall has passed 100 through a horizontal upper portion and disappeared while the horizontal wall has become a vertical wall.

As the carton end flap passes through the channel the portion outside of line *f* will 105 engage the wall, 81, while the inner portion will engage the wall, 80.

Vertical strip 70 begins to taper upwardly shortly beyond the bridge 66 and ends just before the wall 80 becomes truly vertical. 110

A trough 82, similar to 79 but reversed as to top and bottom is disposed on the front side of the machine; this trough is hung from above and does for the front end flap of the carton what trough, 79, does for the rear end flap. The strip, 71, ends at the same point as strip, 70, but tapers downwardly toward its end instead of upwardly. 115

The operation of my machine is as follows: 120

The cartons, as previously mentioned, are supplied to the machine in collapsed form with lips and end flaps extended as shown in Figs. 13-15; this is the form in which they come from the manufacturers. A stack 125 of these cartons is placed in the magazine 33. As the machine is arranged it is important that the cartons be positioned in the magazine as indicated, *i.e.*, with the end flap attached to the bottom of the carton 130

projecting to the rear and lying toward the delivery end of the machine. In this way when the carton is opened up the bottom remains stationary while the top rises and moves forwardly, being pivoted on the lines *k* and *l*.

The machine is now started. During substantially the first quarter revolution of driving shaft, 2, the receiving element 6 of 10 the Geneva stop, and its shaft, 7, will be rotated through 90° thereby advancing the conveyer chain, 17, with its compartments, 19, by a corresponding amount. During this time cam groove, 24, through rod, 27, 15 lever, 28, and link, 30, will have brought the carton pusher fingers, 36, against the lowermost carton in the magazine and will have pushed said carton forwardly upon the magazine table. As the forward outer portion 20 of rear end flap, *e*, passes over the depression, 55, it will be pushed downwardly therein by the spring, 56. Similarly, on the front of the machine, the forward outer portion of end flap, *g*, will be elevated by the 25 boss, 54. In this way the end, flap, *e*, and the lip, *b*, at the rear of the machine, are slightly separated and, similarly, at the front of the machine, the end flap, *g*, and lip, *d*, are separated. As the carton moves 30 forwardly knife, 50, at the rear of the machine will slip between the separated end flap, *e*, and lip, *b*, and the other knife, 50, at the front of the machine will slip between end flap, *g*, and lip, *d*. The outer ends 35 of these knives, owing to the tension of springs, 53, will be thrust entirely into the ends of the carton proper so as to separate the top from the bottom.

Owing to the fact that that portion of 40 cam groove, 24, which controls the inward movement of the pusher fingers subtends more than 90° of arc, the conveyer chain will have stopped before the pusher fingers have reached the limit of their stroke. The 45 carton will, therefore, be brought up firmly against a partition, 18, and, the motion of the pusher fingers continuing, the top of the box will be raised, pivoting upon edges, *l*, and *k*, and the carton completely opened. 50 Just before the carton is thus completely opened up as above, the knife operating screws, 63, will contact with arms, 64, thus forcing the knives outwardly and freeing them from the carton. (See dotted construction Fig. 11).

During this quarter revolution of shaft, 7, sprocket wheel, 13, will have been rotated through one-eighth revolution. This will cause the carton depressing finger, 62, 60 through cam 56', link 59, and crank arm 60, to be brought down upon the carton at an appropriate time so as to seat it firmly in the compartment 19. Owing to the tension of spring, 62', this finger, 62, remains at 65 rest upon the carton after it has been fed

into the compartment of the conveyer chain, as just described, while the main shaft continues its revolution and until the Geneva stop is again actuated on the second revolution of the shaft.

70

As the main shaft, 2, continues to rotate through a trifle less than 180° , pin, 25, remains in the circular part of cam groove, 24, so that the carton pusher fingers remain at the limit of their throw; and for a little 75 more than the last 90° of the first revolution of the main shaft the cam groove, 24, is bringing the pusher finger back to their original position after which time their operations are repeated to bring forward a 80 second carton.

The conveyer chain, being directly connected with and positively driven by the receiving element of the Geneva stop, only moves during the first quarter of each revolution of the main shaft. The advancing of 85 the carton from the magazine end to the delivery end of the machine is, therefore, intermittent.

During the second revolution of the main 90 shaft the carton which has just been placed in a compartment, 19, at position *p*, is advanced to position *q*, and during the third revolution of the main shaft will be advanced to position *r* opposite the center of 95 the cam feeding table 22. Just before the carton reaches this last position the lip *d*, on the front of the machine, will contact with the out-turned end of strip 71 and be turned inwardly so as to partially close the 100 end of the carton. Simultaneously therewith the folder arm, 45, will be actuated through bell crank lever, 43, link, 42, rod, 40 and eccentric, 39 so as to similarly turn in the adjacent lip *e* on the magazine side 105 of the carton.

For each advance of the carton conveyer chain, caused by the movement of the Geneva stop, shaft 14 will rotate through one-eighth of a revolution thereby causing 110 the can feeding table 22 to be turned through one-quarter revolution. This can feeding table contains four compartments seated 90° apart into which the packed sardine cans are successively placed. The table 115 is so set that as the conveyer chain stops with a carton in position *r* opposite the center of the can feeding table, this latter will present a compartment directly in line with the carton (Fig. 3). From this position on 120 the can feeding table the sardine can will be swept into the carton by the sweeping device, 49, actuated through link, 47, operating arm, 46, shaft, 41', bell crank lever, 41, eccentric rod, 40, and eccentric, 39.

125

As the now filled carton continues to advance with successive revolutions of the main shaft the lip *b*, at rear of and toward the delivery end of the machine, will be pressed against the out turned end of strip, 130

70 and be pressed inwardly; at the same time lip folder 45² will be swung downwardly, by means of bell crank lever 43' and cross link, 44, so as to turn in lip, *a*.
 5 All the lips of the carton are now closed but the end flaps are still fully extended.

As the lips, *b*, and, *d*, meet the strips, 70, and, 71, the ends, *e*, and *g*, pass respectively under and over said strips.

- 10 The carton now passes on under bracket, 66, with the end flap, *c*, lying against the machine top and the opposite end flap, *g*, against the under surface of bar, 76 (Fig. 4). End flap, *c*, will thereby be brought under 15 folder plate, 74, and end flap, *g*, over folder plate, 75; at the same time the extreme end portions of each end flap (the parts outside lines, *f*, and, *h*) are caused to meet the strips, 77, and 78, whereby they are turned 20 sharply upwardly and downwardly, respectively.

The carton will now reach the closing troughs, 79, and 82, and the end flaps will, respectively, enter therein with the two 25 parts of each flap on the two sides of the lines, *f*, and, *h*, in contact with the two walls of the trough. Advancing along these troughs the end flaps are swung inwardly by the twist of the trough until, finally, 30 when the carton reaches the position where the channel wall has become truly vertical, the end portions outside of lines, *f*, and, *h*, will be found tucked within the carton between the edges of the lips and the under 35 surface of either the top or bottom of carton as the case may be. The opposite vertical walls of the troughs, 79, and, 82, being the same distance apart as the ends of the carton proper, (lines *i* and *j*) and the guide 40 bars 68, and, 69, being spaced from the machine top by the thickness of the filled carton the several lines along which the lips and end flaps are closed will be sharp and clean cut.

- 45 The filled cartons will, finally, be carried free of the machine at the delivery end thereof, by the conveyer chain.

While I have described my machine as intended for placing packed sardine cans in 50 cartons it is clear that other cans, packages, or even grouped masses of loose material could be arranged to be boxed without making other changes in the machine than could readily be accomplished by mere mechanical 55 skill.

Furthermore, while I have described my machine as one in which the carton conveyer chain is advanced and the can feeding table rotated intermittently, such motion is not 60 essential and slight changes in the individual mechanical movements would permit continuous and uniform motion of these parts within the scope of the invention.

Having described my invention, I claim:

- 65 1. In a machine of the class described, a

conveyer chain having compartments, a magazine for holding stacked collapsed cartons said magazine having a slot in the bottom thereof, a reciprocable pusher finger fitted to said slot and arranged to remove a 70 single carton from the bottom of the stack and place it in a compartment of the conveyer chain, a pair of laterally disposed carton opening knives arranged to slip between the top and bottom of the carton, and means 75 for placing a can in the carton and then closing the carton at each end.

2. In a machine of the class described, a magazine for holding a stack of collapsed cartons, means for sliding a single carton 80 from beneath the stack, means for depressing the bottom end flap of the carton, means for raising the top end flap, a carton opening knife adjacent each end of the carton arranged to slip between the top and bottom 85 of the carton so as to open it, means for withdrawing said knives from the carton, and means for placing a can in the carton and closing the ends of the same upon said can.

3. In a machine of the class described and adapted to place cans in cartons having a bottom end flap at one end and a top end flap at the other end, a table, means for carrying the filled carton along the table 90 with the end flaps extended, a folding plate at each end of the carton spaced therefrom by the thickness thereof and from the end flap by its thickness, and a strip immediately adjacent to but outside the folder plate for 95 bending the outer portion of the end flap toward the carton.

4. In a machine of the class described, in combination with means for filling the carton, folding in the end lips, and folding the 100 outer portion of the end flaps toward the carton, a trough adjacent each end of the carton said trough having two walls adapted to respectively engage the outer and the inner portions of the flaps, said trough being twisted through 90° so as to tuck the end flap into the carton.

5. In a machine of the class described, a magazine holding stacked collapsed cartons, a conveyer chain having compartments, 115 means for placing cartons successively in said compartments, a rotary can feeding table, means for simultaneously moving the conveyer chain and the can feeding table to bring a can opposite a carton, an oscillating sweeping device for pushing the can into the carton and means for thereafter closing the carton at each end.

6. In a machine of the class described, a magazine holding stacked collapsed cartons, 125 an intermittently movable conveyer chain having compartments, a reciprocable pusher finger arranged to remove a single carton from the stack and push it against a front wall of a compartment, the movement of the 130

finger continuing with respect to that of the conveyer chain until the carton is completely opened and seated in the compartment, and means for thereafter placing a can in the carton and closing the ends of the carton thereupon.

5 In testimony whereof, I have hereunto set

my hand in the presence of two subscribing witnesses.

ROBERT F. JONES.
